UNITED STATES PATENT OFFICE.

GODFRIED SCHOCK, OF CLEVELAND, OHIO.

AUTOMOBILE DIRECTION SIGNAL.

Application filed April 7, 1926. Serial No. 100,232.

The main object of this invention is to provide a signalling device positioned at the rear of the vehicle for indicating to the vehicles following that a change of direction is to be made.

Another object is to provide a signalling device at the rear of the vehicle which is operable from the operator's seat.

The above and other objects will become apparent in the description below, in which characters of reference refer to like-named parts in the drawing.

Referring briefly to the drawing, Figure 1 is a longitudinal partly sectioned elevational view of one of the signal devices, said devices being applied in pairs to the vehicle.

Figure 2 is a top plan view of Figure 1.

Figure 3 is a plan view of a vehicle shown in broken lines having signals applied thereto.

Referring in detail to the drawing, the numeral 10 indicates a hollow casing. It is to be noted that these casings are to be duplicated, one for each side of the vehicle at the rear. One of the casings has a relatively large annular housing 11 secured to the rear side. Said annular housing is surrounded by a smaller housing 12.

Both housings 11 and 12 have an open face which is covered with glass 13. On the glass in the smaller housing, the word Go is inscribed, and on the glass covering the larger housing, the word Stop is inscribed. These housings are provided with filament lamps not shown on the drawing which are actuated in the usual manner to illuminate alternately the housings. The same casing which carries the housings 11 and 12 has a post 14 secured thereto which extends upwardly and has a reflector 15 mounted at its upper end. Within the reflector, a filament lamp 16 is fixed. One end of the casing 10 is closed by a wall 17, the opposite end being open and cut away to provide two spaced-apart parallel extending side walls 18 and 19 between which a pair of semi-circular tongues 20 form part of a movable housing 21. A short spindle 22 is fixed in the tongues and has a bevelled gear 23 secured thereon. This spindle is rotatably journalled in openings provided in the parallel walls 18 and 19 and permits the housing 21 to be rotated from the horizontal to the vertical when the bevelled gear 23 is rotated. A shaft 24 extends thru the entire length of the housing from one

end to the other. One end of this shaft has a bevelled pinion gear 25 fixed thereon which meshes with gear 23. This shaft is supported in bearings 26 located near opposite ends of the casing. The end of the shaft opposite to where the pinion 25 is located receives an additional gear 27 which is engaged by another gear 28 mounted on a shaft 29. The shaft 29 extends at right angles to the shaft 24 forwardly in the body of the car to the operator's compartment, at which end crank arms 30 are mounted. The housing 29 is fashioned as an arrow pointing outwardly and has a glass face 31 on which the word Turn 32 is inscribed. The housing is adapted to have mounted therein a filament lamp, not shown on the drawing, which is selectively illuminated thru a circuit and switch located in the operator's compartment.

The signalling device is used for indicating a change of direction of the vehicle on which said device is mounted. When desiring to turn left, the shaft 29 of the left casing is rotated in the proper direction. Rotation of this shaft is communicated to the gears 28 and 27, which latter being fixed to the shaft 24, rotates it, causing the pinion 25 fixed on the opposite end of the shaft and meshing with the gear 23 to rotate the latter and swing the housing 21 from the position shown in dotted lines in Figure 1 to the horizontal position illustrated in full lines. At the same instant, a switch may be closed by the operator to illuminate the area behind the glass face 31 of the particular housing so that a visible signal is given.

It is to be noted that changes in construction may be made without departing from the spirit and scope of the invention.

I claim:

1. A signalling device comprising a rotatable housing fashioned as an arrow, a glass face in said housing, a casing supporting said housing, said casing having a fork at one end, tongues on said movable housing positioned intermediate said fork, a spindle rotatably journalled in said fork and rigid with said casing, a bevel gear on said spindle and means engaging said gear to rotate said housing from the vertical to the horizontal position or vice versa.

2. A signalling device comprising a rotatable housing fashioned as an arrow, a glass face in said housing, a casing supporting said housing, said casing having a pair of

- vertical parallel spaced-apart walls at one end, tongues on said movable housing positioned between the parallel walls of the casing, a spindle rotatably journalled in said walls and rigid with said casing, a bevelled gear rigid with said spindle adjacent one tongue of the housing, a shaft rotatable in said casing, gears on both ends of said shaft, and means for rotating said shaft from the operator's position in the vehicle.
3. A signalling device comprising a rotatable housing fashioned as an arrow, a glass face in said housing, a casing supporting said housing, said casing having a pair of vertical parallel spaced-apart walls at one end, tongues on said movable housing posi-

tioned between the parallel walls of the casing, a spindle rotatably journalled in said walls and rigid with said casing, a bevelled gear rigid with said spindle adjacent one tongue of the housing, a shaft rotatable in said casing, gears on both ends of said shaft, a shaft extending at right angles to the first-named shaft, a gear fixed to said last-named shaft in the housing meshing with one of the gears on the first-named shaft, and a crank arm at the opposite end of the last-named shaft for rotating the latter to rotate the movable housing from the horizontal to the vertical position or vice versa.

In testimony whereof I affix my signature.
GODFRIED SCHOCK.
